Inventor:
Joseph Komorous,
By appointment, Sec. Chittenden & Wilcox,
Attest:

UNITED STATES PATENT OFFICE.

JOSEPH KOMOROUS, OF RIVERSIDE, ILLINOIS, ASSIGNOR TO PARISIAN NOVELTY COMPANY, OF CHICAGO, ILLINOIS, A CORPORATION OF ILLINOIS.

BRUSH.

Application filed May 31, 1923. Serial No. 642,671.

To all whom it may concern:

Be it known that I, JOSEPH KOMOROUS, a citizen of the United States, residing at Riverside, in the county of Cook and State 5 of Illinois, have invented a new and useful Improvement in Brushes, of which the following is a specification.

My invention relates, more particularly, to brushes of the type comprising a body 10 portion equipped with bristles, and a top portion formed of sheet material crimped upon the body portion to secure it in position thereon, the sheet material, by way of example, being sheet metal covered with 15 celluloid, or other suitable flexible material.

The type of brushes referred to are commonly of relatively inexpensive construction and are most generally provided as advertising novelties bearing advertising matter, whereby the matter of cost of production is a very important item, it being necessary for their extensive production, that they be capable of being produced at a very low cost.

The practice commonly followed in the manufacture of brushes of the type referred to, particularly as advertising novelties, is to form the body of the brush of wood to which the bristles are secured, and to mount 30 the wood body in a metal bezel to which the celluloid-covered top plate, forming the back of the brush, is secured. Such constructions, however, are quite expensive to manufacture and furthermore cannot, in the 35 commercial manufacture of the brushes, be provided of elongated form and particularly of such form that opposite edges of the body of the brush are straight, or substantially straight, because of the shrinking of 40 the wood and the consequent looseness of fit of the wood bodies in the bezels, which prevents the crimping of the top plates upon the bezels into the desired interlocking position.

My object is to provide a construction of brush of the general type above referred to which shall not only be more economical of manufacture than brushes of this general type as hitherto constructed, but which may 50 be provided in any desirable shape, even of oblong form with its opposite edges substantially straight and with their top portions securely crimped in place, and forming structures, the parts of which are firmly 55 and rigidly secured together.

Referring to the accompanying drawing:—

Figure 1 is a perspective view of a brush constructed in accordance with my invention; and Figure 2, an enlarged section 60 taken at the line 2—2 on Figure 1 and viewed in the direction of the arrows.

The brush shown is formed of a body portion 3 of any suitable material capable of being molded into the desired form. Such, 65 for example, as that commonly used in the manufacture of brushes having bristles embedded therein by molding the body material about the ends of the bristles; the bristles represented at 4 being embedded 70 in the body portion, as shown. The body portion 3 is of the same marginal contour as the back of the finished brush to be produced, it being surrounded at its marginal portion by a bezel 5, preferably of metal, 75 which preferably is formed at its lower edge with a continuous, inwardly-projecting flange 6 by preference inset in the under surface of the body 3, as shown. The upper portion of the bezel 5 is outwardly deflected 80 throughout its extent, as represented at 7, to form a portion for interlocking with the top portion of the brush which is represented at 8 and is shown as formed of a metal plate 9 provided with an endless depending 85 flange 10, the plate 9 being covered with a sheet 11 of celluloid, or other desirable material, which extends over the entire upper surface of the plate 9 and the outer and inner surfaces of the flange 10, the top portion referred to, of the brush, being crimped 90 at its flange 10 about the outwardly deflected portion 7 of the bezel for securely fastening the top portion to the bezel and holding the sheet 11 clamped in place. 95

The material forming the body portion being thus of a character which does not shrink or warp under normal conditions, the parts of the brush may be assembled to form long after the body portion has been 100 constructed. In the manufacture of the brushes it is preferred, however, that the body portion 3 be molded to shape into the bezel 5, the bezel having been preliminarily introduced into a mold presenting a cavity 105 of a shape and size corresponding with the shape of the brush it is desired to be produced, and the material to form the body portion 3 then introduced into the mold to fill the bezel 5, as shown. It will, of course, 110

- be understood that if desired the body portion 3 may be formed as a separate structure in any desirable way and thereafter assembled with the bezel.
- 5 The upper surface of the body portion 3 preferably has embedded therein a sheet 12 of material to form a binder for the material of the body and prevent the body from breaking should it be dropped upon the
- 10 floor before being assembled with the top plate portion. Any suitable material may be used for this purpose, as for example, cardboard.

From the foregoing, it will be understood that brushes of any desirable form, even those of oblong shape and having parallel, or substantially parallel, sides, may be manufactured and no difficulties in the crimping of the top plates in place on the bezels, are 20 presented, inasmuch as the body portions closely fit the bezels.

While I have illustrated and described a particular construction embodying my invention, I do not wish to be understood as 25 intending to limit it thereto as various changes and modifications may be made in the structure shown, without departing from the spirit of my invention.

What I claim as new, and desire to secure 30 by Letters Patent, is:

1. A brush comprising, in combination, a body portion of set plastic material having bristles embedded therein, a retaining band

surrounding said body portion and provided at its upper end with an outwardly-extending peripheral flange, the body portion extending substantially flush with the upper edge of the band whereby the band is reinforced against flexure in the crimping of the cover, and a cover for said body extending over the top of said body and crimped into engagement with the flange of said band.

2. A brush comprising, in combination, a body portion of set plastic material having bristles embedded therein, and having a sheet of binding material embedded and anchored in its upper portion and a cover secured in place about said body portion and extending over the same in spaced relation to the upper surface thereof and to said binding strip.

3. A brush comprising, in combination, a body of set plastic material having bristles embedded therein, a retaining band surrounding said body portion and provided at its upper end with an outwardly-extending peripheral flange and a cover for said body formed of an inner and an outer member the edges of which extend over the top of said body and are crimped into engagement with the flange of said band, the outer member of said cover being of material adapted to receive printing or decorative matter.

JOSEPH KOMOROUS.
